UNITED STATES PATENT OFFICE.

HENRY S. HOPKINS, OF BROOKLYN, NEW YORK.

DRYING APPARATUS.

1,034,112.

Specification of Letters Patent. Patented July 30, 1912.

Application filed August 10, 1911. Serial No. 643,469.

To all whom it may concern:

Be it known that I, HENRY S. HOPKINS, a citizen of the United States, residing at Brooklyn, in the county of Kings and State of New York, have invented certain new and useful Improvements in Drying Apparatus, of which the following is a specification.

This invention relates to apparatus for drying in a continuous sheet or web, a material such as paper or cloth which has been subjected to some surface finishing or preparatory operation, such as coloring, top sizing, gumming, printing, etc.

The principal objects of this invention are: first, to devise a drier through which the material can be passed in a continuous sheet or web directly from the coating machine, and then from the drier directly to the winding mechanism; second, to prevent the curling up of the edges of the material while it is being dried; third, to provide means whereby the temperature of the drying blast and the amount of moisture contained therein may be regulated at will at any point of the passage of the material through the drier.

Further objects will appear from the detailed description and will be fully pointed out in the claims.

In the accompanying drawing which illustrates this invention: Figure 1, is an elevation and Fig. 2 is a plan of one form of my drying apparatus. Fig. 3 is a section taken along line III—III in Fig. 1. Fig. 4 is a section taken along line IV—IV in Fig. 1. Fig. 5 is a fragmental detail view. Fig. 6 is a section taken on line VI—VI in Fig. 5, the lateral dimensions of parts being exaggerated for the sake of clearness. Fig. 7 is an elevation and Fig. 8 is a plan of a modified form of my apparatus. Fig. 9 is a section taken on line IX—IX of Fig. 7.

Referring to Figs. 1 to 4, the numeral 1 indicates generally a coating machine from which the coated material 2 is fed to my improved drier. The latter consists of a casing 3 divided into a plurality of compartments, 4, 5, 6, 7, 8, etc. I have shown only five of these compartments by way of illustration, but it may be understood that any desired number of compartments may be used. In the first and last of these compartments are mounted drums 9 and 10 actuating an endless conveyer 11 which carries the paper through the drier. Drum 9 may be driven

from a pulley 12 which is in turn driven from the same jack shaft which drives the coating machine. In this way it is assured that the conveyer will travel at the same speed as the paper is fed from the coating machine. The conveyer consists of a belt having transverse rods 13, which are guided on angle irons 14 secured to the inner side wall of the casing. Slots 15 are provided in the partitions 16, separating the compartments, and through which the conveyer belt passes, together with the paper carried thereby.

As the material passes through the casing or drying chamber it is subjected to blasts of air which are directed downwardly upon the material so as to cause it to lie flat upon the belt, and prevent its curling along the edges as it dries. These blasts of air are directed from the top of each compartment, contain varying amounts of suspended moisture and are also of different temperatures. Into the compartment adjacent to the point of exit of the material from the apparatus, is forced a hot dry blast, while into the compartment adjacent to the point of entrance of the material into the drier, is forced a blast of a lower temperature and containing a greater amount of suspended moisture. The blasts in the intermediate compartments, normally, increase gradually in amount of suspended moisture, and decrease in temperature.

To obtain the dry hot blast I mount on the top of the last compartment a heater 17 through which air is forced by a blower 18. This blast enters the compartment through opening 19, passes over the paper, past its edges, and down into the portion of the compartment below the top run of the conveyer belt. From there it is exhausted and forced down upon the material in the next compartment, and so on. As the air thus passes through the drier it gathers up moisture and falls in temperature. The exhausting and forcing of the air are accomplished by a series of fans mounted in the drier, one in each compartment. A shaft 21 is journaled in the walls of each compartment, on which shaft is mounted a fan 22 located in a tubular member 23 extending from the wall. A conduit or flue 24 extends from the tubular member 23 of one compartment to the top of the next compartment, where it terminates in a diverging mouth 25, having the

general shape of an inverted hopper. The latter directs the blast so as to be distributed substantially evenly upon the entire surface of the material.

5 To adjust the opening presented for the escape of the air from the top to the bottom of each compartment, I provide slidable or otherwise adjustable members 26. Rods 27 are connected to these slides and project through openings in the walls of the casing, and terminate in handles 28, by means of which the slides can be adjusted from the exterior of the apparatus. These slides regulate the air pressure upon the material, and also serve to adjust the apparatus for different widths of material to be dried. These slides, moreover, are so shaped and can be so adjusted as to concentrate the blast upon the edges of the sheet so as to insure its lying flat upon the conveyer. However, this concentration of the blast is not necessary in all cases. With some qualities of paper and coatings such concentration is not necessary. Sight holes 29 are provided for observing the condition of the material in any compartment.

Upon the fan shafts I mount cone pulleys 30 which are adapted to be driven from cone pulleys 31, mounted on a shaft 32, running parallel with the length of the drier. These pulleys may be driven from each other by quarter turn belts. By shifting the belt along the pulleys any desired strength of blast can be obtained for any compartment. This provides for the adaptation of the blast to various conditions of material to be dried.

If it should be found that the amount of moisture suspended in the blast becomes excessive at any stage of its passage through the apparatus, a dry blast may be introduced into any compartment by properly adjusting dampers 33, located in pipes 34, connected to flue 35, extending from the heater. The moist air may be exhausted by opening dampers 240 in flues 24. If, on the other hand, it is found that the paper is drying too rapidly at any point, a jet of steam may be introduced into the bottom of any compartment, and thus increase the amount of suspended moisture in the blast, and hence decrease the rapidity of drying. The steam may be introduced by means of small pipe sections 36, connected to pipe 37, and containing valves 38.

When paper is coated, the bottom side is unavoidably covered for a short distance from the edge. I take advantage of this circumstance to provide auxiliary means for assisting the air pressure in causing the sheet to lie flat upon the conveyer, and prevent its wrinkling or curling. Upon the screen 39 of the conveyer I place strips 40 of fibrous material, preferably muslin or the like (Figs. 5 and 6). The bottom of the

paper adjacent its edge will adhere to the fibrous material and thus assist the air blast in keeping the paper flat upon the conveyer.

In the construction illustrated in Figs. 7, 8, and 9, I show a modified form of my drying apparatus in which hinged fins 41 are used instead of slides for adjusting the conditions of the blast to various widths and conditions of material. The conduits or flues 24^a extend directly into the top of the casing 3^a which is formed with sloping walls 42 having covers hinged thereto. The covers are formed in two sections 44 and 45 hinged together. This sectional construction makes it possible to open the covers one section at a time, and thus avoid interference with the belts which drive the fan shafts. By providing these covers for each compartment it is merely necessary to open one of these when it is desired to exhaust the moist air from any compartment. When a cover is opened for the purpose of getting at the material, the adjacent fin can be swung inwardly and out of the way, as shown in Fig. 9. Rods 46 are pivoted to the fins and project through slots 47 in the casing and terminate in handles 48. The rods are toothed to coöperate with the walls of the slots to hold the fins in any desired adjusted position. Sight holes 49 are provided at the top of each compartment to observe the condition of the material. In all other respects this modified construction may be made substantially the same as the construction illustrated in Figs. 1 to 4.

It will be seen from the foregoing that I have devised a drier through which a continuous length or web of moist material can be passed continually and dried, and then passed on directly to any mechanism for further handling it, as for instance a winding mechanism for winding the sheet or web into a roll. This prevents the delay in handling which arises when the material is allowed to dry in ordinary atmosphere, and also saves a large amount of floor space.

It will further be seen that I have provided means for preventing the edges of the material from curling while drying, and thus eliminating a very great source of annoyance and waste. The material is caused to lie flat upon the conveyer, either by the strength of the blast itself or by the blast assisted by the adherence of the edges of the material to the conveyer. The decrease of pressure below the apron produced by the suction of the fans also assists in keeping the sheet flat upon the conveyer. It will also be clear that the drying apparatus disclosed herein is sufficiently flexible in its operation to be adapted to a great variety of conditions. Provision is made for adjustment for various widths of material and also for obtaining practically any desired

rate of drying. The latter adjustment can be made, by varying the strength of blast, which may be done by shifting the belt along the cone pulleys on the fan shaft in any compartment; by increasing the amount of suspended moisture in the blast by turning on a jet of steam in any compartment; or by decreasing the amount of suspended moisture in the blast, and increasing its temperature by introducing a hot dry blast and exhausting the moist air at any compartment. Furthermore by subjecting the material first to a moist blast, and then to increasingly drier blasts, too rapid drying at the beginning is prevented and thus the formation of a hard crust on the surface is avoided. This defect arises when surface coated materials are dried too rapidly at the beginning of the drying operation, and results in the retardation of the complete drying. However it is clear that with my construction I can if I may desire, exhaust all of the moist air at any compartment and introduce the dry blast into the following compartments. This may be done when it is desired to accelerate the drying.

Various modifications may be made, without departing from the spirit and scope of the invention as defined in the appended claims.

I claim:

1. In apparatus for drying sheets, a casing divided into a plurality of compartments, a conveyer belt passing through the walls of the compartments and adapted to carry a sheet to be dried, and means for directing a blast of air down upon the sheet and past its edges so as to cause it to lie flat upon the belt.

2. In apparatus for drying sheets and fabrics, a conveyer adapted to carry a sheet to be dried, means for directing a blast of air down upon the sheet, and means for concentrating the pressure along the edges of the sheet so as to cause it to lie flat upon the conveyer.

3. In apparatus for drying sheets, a casing divided into a plurality of compartments a conveyer belt passing through said compartments and adapted to carry a sheet to be dried, means for forcing a blast of air down upon the material in each compartment and past the edge of the sheet, said means being adapted to utilize the air exhausted from one compartment for forcing into the next compartment.

4. A drier, comprising a casing divided into a plurality of compartments, a conveyer passing through the compartments and adapted to carry the material to be dried, an air inlet at one end of the casing and an air outlet at the opposite end of the casing, means in each compartment for forcing a blast of air down upon the material in the next compartment, and connec-

tions for utilizing the same air repeatedly by causing it to move progressively through the various compartments from its point of entrance into, to its point of exit from the apparatus.

5. A drier, comprising a casing divided into a plurality of compartments, means for forcing a blast of air down upon the material in each compartment, said blast having a progressively increasing amount of moisture suspended therein, starting from the compartment adjacent to the point of exit of the material from the drier to the compartment adjacent to the point of entrance of the material into the drier, and connections for forcing an auxiliary dry blast into any compartment.

6. A drier comprising a casing divided into a plurality of compartments, means for forcing a blast of air down upon the material in each compartment, said blast having a progressively increasing amount of moisture suspended therein, starting from the compartment adjacent to the point of exit of the material from the drier, to the compartment adjacent to the point of entrance of the material into the drier, means for regulating the strength of blast in any compartment, and connections for forcing an auxiliary dry blast into any compartment.

7. A drier comprising a casing divided into a plurality of compartments, means for forcing a blast of air down upon the material in each compartment, said blast having a progressively increasing amount of moisture suspended therein, starting from the compartment adjacent to the point of exit of the material from the drier, to the compartment adjacent to the point of entrance of the material into the drier, means for regulating the strength of blast in any compartment, connections for forcing an auxiliary dry blast into any compartment, and means for regulating the strength of said dry blast.

8. In apparatus for drying sheets and fabrics, the combination of a casing divided into a plurality of compartments, a conveyer passing through the compartments and adapted to carry the sheet to be dried, means for forcing a blast of air down upon the sheet, and adjustable means for directing the blast so as to correspond to the width of the sheet to be dried.

9. A drier, comprising a casing divided into a plurality of compartments, a conveyer passing through the compartments and adapted to carry the material to be dried, means for forcing a blast of air into each compartment and down upon the material, the degree of moisture in said blast being normally greater for the compartments near the point of entrance of the material into the casing than for the compartments near the point of exit of the material

from said casing, and means for increasing at will the amount of suspended moisture in any compartment in the drying chamber.

10. In apparatus for drying material in a continuous sheet or web, the combination of a drying chamber divided into a plurality of compartments and through which the sheet is adapted to pass, means for forcing a blast of air into each compartment and down upon the sheet, the degree of moisture in said blast being normally greater for the compartments near the point of entrance of the sheet into the chamber than for the compartments near the point of exit of the sheet from the chamber, and means for increasing and decreasing at will the relative amount of suspended moisture in any compartment in the chamber.

11. A drier, comprising a casing divided into a plurality of compartments, a conveyer in said compartments for carrying the material to be dried, means for forcing a blast of air down upon the material in each compartment, the amount of moisture suspended in said blast increasing progressively from the compartment adjacent to the point of exit of the material from the casing to the point of entrance of the material into the casing, means for forcing an auxiliary dry blast into any compartment, and means to allow the moist air to be exhausted from any compartment.

12. A drier, comprising a drying chamber divided into a plurality of compartments, a conveyer passing through the compartments and adapted to carry a sheet to be dried, a fan located in each compartment to the top of the next compartment, and below the conveyer, a conduit extending from the fan of each compartment, said fans being adapted to force the air from one compartment down upon the material passing through the next compartment and past the edges of the sheet, thus causing a downward pressure upon the top of the sheet throughout its width and a suction below the sheet.

13. A drier, comprising a drying chamber divided into a plurality of compartments, a conveyer passing through the compartments and adapted to carry the material to be dried, a fan located adjacent the exterior side wall of each compartment, and below the conveyer, a conduit extending from the fan of one compartment to the top of the next compartment, said fans being adapted to force the air from one compartment down upon the material passing through the next compartment, shafts transverse to the length of the chamber, on which said fans are mounted, and a shaft running lengthwise of the chamber and driving the fan shafts.

14. A drier, comprising a drying chamber divided into a plurality of compartments, a conveyer adapted to carry the material to be dried and means for forcing a blast of air

through the chamber in a direction generally opposite to the direction of motion of the material, a heater located adjacent the point of exit of the material from the drying chamber, and adapted to heat and dry the air initially forced into said chamber, said air blast increasing in amount of suspended moisture and decreasing in temperature as it circulates through the compartments of the drying chamber and means for exhausting the moist air and supplying a dry blast at the intermediate compartments.

15. In an apparatus for drying material in a continuous sheet or web, a drying chamber; a conveyer in said chamber adapted to carry the sheet to be dried, means for forcing a blast of air down upon the material, and adjustable fins for directing the air blast in accordance with the width of the sheet so as to impinge on substantially the entire width of the sheet and escape past the edges of the sheet to a point below the conveyer apron.

16. In apparatus for drying material in a continuous sheet or web, a drying chamber, a conveyer in said chamber adapted to carry the sheet to be dried, means for forcing a blast of air down upon the material and adjustable pivotally mounted fins for directing the air blast in accordance with the width of the sheet past the edges of the sheet to a point below the apron.

17. A drier, comprising a drying chamber divided into a plurality of compartments, a conveyer in said compartments for carrying the material to be dried, pivotally mounted fins in each compartment adapted to direct a blast of air down upon the material, and a movable cover for each compartment, said fins and cover being adapted to be swung in a direction away from the material so as to permit easy access thereto.

18. In a drier for drying material in sheets, a conveyer for carrying the material to be dried, and means on the conveyer adapted to adhere to the edges of the material so as to prevent the latter from wrinkling or curling.

19. In apparatus for drying material in sheets, an endless conveyer belt for carrying the material to be dried, a strip of fibrous material on said belt and adapted to cause the edges of the first mentioned material to adhere thereto.

20. In apparatus for drying sheets coated on one side, the coating extending over onto the bottom of the sheet adjacent the edge a conveyer for carrying the sheet and means on the conveyer adapted to adhere to the partially coated bottom side of the sheet, causing the latter to lie flat upon the conveyer.

21. In apparatus for drying material in a continuous sheet or web, a conveyer adapted to carry the material to be dried, means for directing an air blast downwardly upon the

material and auxiliary means for causing the edges of the material to adhere to the conveyer, said auxiliary means coöoperating with the air blast to cause the material to lie flat 5 upon the conveyer.

22. An apparatus for drying sheets, comprising a casing divided into a plurality of compartments, means for forcing a dry blast down upon the sheet at certain of the compartments and means for exhausting to the atmosphere the moist air from certain other of the compartments, the dry blast being adapted to be forced from one compartment into another and increasing in amount of

suspended moisture contained therein up to 15 the point of its exhaust into the atmosphere.

23. A drier, comprising a casing, a conveyer passing through the casing and carrying a sheet to be dried, and means for decreasing the pressure below the sheet and 20 directing a blast down upon the top of the sheet and past its edges, so as to cause the sheet to lie flat upon the conveyer.
